UNITED STATES PATENT OFFICE.

WILLIAM H. ROYSTER, OF MIDWAY, VIRGINIA.

CHURN.

SPECIFICATION forming part of Letters Patent No. 293,195, dated February 5, 1884.

Application filed August 10, 1883. (No model.)

To all whom it may concern:

Be it known that I, WILLIAM H. ROYSTER, a citizen of the United States, and a resident of Midway, in the county of Halifax and State of Virginia, have invented certain new and useful Improvements in Churns; and I do hereby declare that the following is a full, clear, and exact description of the invention, which will enable others skilled in the art to which it appertains to make and use the same, reference being had to the accompanying drawings, which form a part of this specification, and in which—

Figure 1 is a side elevation of my improved churn. Fig. 2 is a plan or top view of the same, and Fig. 3 is an end view.

Similar letters of reference indicate corresponding parts in all the figures.

My invention has relation to vibrating-body churns; and it consists in the improved construction of the same, which will be hereinafter more fully described and claimed.

In the accompanying drawings, A denotes the frame of my improved churn, in one side of which is journaled the toothed drive-wheel B, which is operated by a crank, C, and meshes with the pinion D upon a short shaft, E, having a fly-wheel, F, at its inner end. The wheel F has a wrist-pin, G, which connects by the connecting-rod or pitman H with a vibrating frame composed of parallel side pieces, I, and end pieces, J. The vibrating frame I J is supported upon four springs, K, one at each corner, the lower ends of which are fixed firmly in the cross-bars L of frame A. The sides I I are recessed at M to form boxes or bearings for the trunnions of the cylindrical churn-body or cream-receptacle O, which is made of glass or stone ware, so that it may be readily kept clean and sweet. P is the cover, which is fixed in place by a binding-screw, Q.

R is a set-screw, which is inserted through one of the end pieces of frame I J, bearing with its inner end against the body of the cylindrical cream-receptacle O. The bottom part of the churn is made heavier than the top part, preferably by placing the trunnions

nearer to the top than to the bottom, so that by releasing screw R the churn will of itself 50 drop into the vertical position shown in dotted lines, when, by removing the cover, it may be tilted so as to pour out the buttermilk into a receptacle placed below, after which the butter can easily be removed. The butter will 55 form in the shape of a ball inside of the churn-body O, expelling every particle of buttermilk, and after the buttermilk has been removed from the churn, and by pouring water into it, the newly-made butter will be thoroughly washed by simply operating the crank.

The churn may be readily removed from its reciprocating frame whenever desired by releasing the spring-catches S from the trunnions, said catches consisting of pieces of 65 spring-wire, one end of which is bent into a hook shape, and fastened to the sides I by staples T, while the other end is bent at right angles, and provided with a projection, U, by taking hold of which the catch can readily be 70 released or unshipped from the trunnion.

Having thus described my invention, I claim and desire to secure by Letters Patent of the United States—

1. The combination of the frame A, drive-wheels B, D, and F, shaft E, pitman H, vibrating frame I J, fixed and supported upon the springs K, and having the boxes M and set-screw R, cylindrical churn-body O, having trunnions N, and spring-catches S, the whole 75 constructed to operate substantially as and for the purpose shown and set forth.

2. In a vibrating-body churn, the combination of the vibrating spring-supported frame I J, having the boxes or bearings M, churn-body O, having trunnions N, set-screw R, and spring-catches S, substantially as and for the 85 purpose shown and set forth.

In testimony that I claim the foregoing as my own I have hereunto affixed my signature in 90 presence of two witnesses.

WILLIAM H. ROYSTER.

Witnesses:

AUGUST PETERSON,
ARTHUR L. MORSELL.
